UNITED STATES PATENT OFFICE.

JULIAN H. KENDIG, OF PITTSBURGH, PENNSYLVANIA.

DESIGN FOR A STRAIN-INSULATOR.

52,139.

Specification for Design.

Patented July 2, 1918.

Application filed February 28, 1917. Serial No. 151,588. Term of patent 14 years.

To all whom it may concern:

Be it known that I, JULIAN H. KENDIG, a citizen of the United States, residing at Pittsburgh, in the county of Allegheny and State of Pennsylvania, have invented a new, original, and ornamental Design for Strain-Insulators, of which the following is a specification, reference being had to the accompanying drawing, forming a part thereof.

Figures 1 and 2 are side elevation views of

the insulator taken at right angles to each other; Fig. 3 is a plan view of the insulator; and Fig. 4 is an elevation view of the insulator taken in the direction of the arrows shown in Fig. 3.

I claim:

The ornamental design for a strain insulator as shown.

JULIAN H. KENDIG.
